GAME SHEET

John A. Bauer, Detroit, Mich.

Application April 12, 1954, Serial No. 29,946

Term of patent 7 years

(Cl. D34—5 (8))

To all whom it may concern:

Be it known that I, John A. Bauer, a citizen of the United States, residing at Detroit, Michigan, have invented a new, original, and ornamental Design for a Game Sheet, of which the following is a specification, reference being had to the accompanying drawing, forming part hereof.

The figure is a top plan view of a game sheet, showing my new design.

The game sheet is of conventional thickness, and the back thereof is substantially plain.

I claim:

The ornamental design for a game sheet, as shown and described.
